UNITED STATES PATENT OFFICE.

OSCAR FALKENWALDE, OF BALTIMORE, MARYLAND, ASSIGNOR OF ONE-EIGHTH TO
CHARLES F. STAUFFEN, OF BALTIMORE, MARYLAND.

DOWNDRAFT-BURNER.

1,317,869.

Specification of Letters Patent.

Patented Oct. 7, 1919.

Application filed March 7, 1918. Serial No. 221,030.

To all whom it may concern:

Be it known that I, OSCAR FALKENWALDE, a citizen of the United States, and resident of the city of Baltimore, State of Maryland, 5 have invented certain new and useful Improvements in Downdraft-Burners, of which the following is a specification.

This invention relates to a burner for furnaces adapted to heat residences by hot 10 water, hot air or steam, or to form the heat generating units of power plants. The fuel is hydrocarbon liquid, usually kerosene, fuel oil or the like, vaporized in the burner and burned in combination with water vapor 15 and an excess of air.

In accordance with the principles of the invention, the fuel in liquid form is flowed over a heated surface in the presence of an air draft and a sufficient supply of water 20 vapor. A portion of the air draft forces the resulting flame against the heated surface on which the fuel is being vaporized thus maintaining the desired temperature of the vaporizer and mixing the air, water and 25 vaporized hydrocarbon under the condition of high temperature necessary to complete combustion and the most efficient production of heat from the fuel.

In the preferred form of the invention, 30 the heated surface is the external surface of an upright, slightly truncated metal cone. The main portion of the air current is drawn directly down on the cone so that the peak or upper portion is kept comparatively cool. 35 The liquid hydrocarbon fuel is fed to the upper extremity or truncated end of the cone and flows down over it toward the base. At the bottom of the cone there is a metal basin which during combustion attains a high tem- 40 perature. This is perforated, the perforations being directed toward the surface of the cone and the draft of the furnace established in any convenient manner, sets up an air current through each of these apertures 45 against the surface of the cone. This, with the down draft, supplies air for combustion and serves to blow the flame against the sur- face of the cone, keeping it at the requisite 50 temperature to vaporize the fuel completely as it flows down the surface of the cone.

In the first form of the invention illus- 55 trated, there is a thick metal water recep- tacle immediately beneath the perforated portion just described. Water is dropped into this receptacle from the supply and the

temperature of the receptacle is kept suf- ficiently high by the proximity of the heated parts of the burner to turn the water into steam which rises to the vicinity of the in- ward air currents and is thus drawn in and 60 supplied to the flame in the proper quantities to combine with the gases and effect com- plete combustion, leaving no carbon deposit whatever.

In the present installations, the burner is 65 substituted for the grate in the usual furnace, the grate opening being completely closed and suitable filler plates being supplied in each instance to fit the particular installa- 70 tion and fill the grate opening around the burner. The water receptacle or evaporator is below the transverse partition thus formed and the air openings, some of which are ra- 75 dial near the bottom of the cone as described and others of which pass upward releasing the air in a downward direction on the top of the cone, all have their intake ends at the bottom of the transverse partition so that the pressure or suction necessary to supply 80 sufficient air for complete combustion results from the furnace draft whether it be natural or forced. The water fed beneath the burner is turned into steam in the vicinity of these 85 intake openings and supplied with the air to the place of combustion.

To render the combustion of the carbon complete, water is also supplied to the fur- nace from above, preferably through a coil 90 which is heated by the products of combus- tion or otherwise. This water is, in the pre- ferred form of the invention dropped on the top of the down draft air duct on a suitable surface provided for this purpose.

I have illustrated a second form of the in- 95 vention, particularly adapted for use in in- stallations where the available draft is less than that found advantageous to the opera- tion of the first form of the invention. In this type, the water supply is in no wise de- 100 pending upon the draft. The water recep- tacle below the burner is omitted and the water is carried up to the hot surface from which the fuel is evaporated and released at that point, that is, the water and the fuel are both evaporated by flowing them over 105 the same hot surface against which the flame is blown by the air draft. In this type of burner, the evaporator is preferably conical and water is supplied from above to mingle 110 with the products of combustion to combine

with any surplus carbon or high carbon gases which may be released and air is also supplied by down draft as in the first type.

In the accompanying drawings I have 5 illustrated two forms of hydrocarbon burner embodying the various features of my invention.

Figure 1 is a side elevation of the first form, the furnace walls being indicated dia- 10 grammatically;

Fig. 2 is a plan of the burner;

Fig. 3 is an elevation partly in section on the line 3, 3 of Fig. 2;

Fig. 4 is a plan of the burner casting 15 with the air duct casting removed; and

Fig. 5 is an elevation of the second form corresponding to Fig. 3, partly in section.

Referring to the drawing by numerals, the 20 installation illustrated in Figs. 1 to 4 consists of a base plate 1, a down draft air duct member 2, a water receptacle 3, and a suitable filler plate or means 50 for fastening and supporting the base plate in the furnace. The base plate with the filler forms 25 a transverse partition across the furnace, the joints being preferably made tight with cement. This transverse partition is best substituted for the grate. The filler plate is best made in sections for convenience in inserting through the doors. The base plate 30 1 is illustrated in plan in Fig. 4. Specifically, in the form shown it consists of a circular disk 4 having a central depression 5 with radial apertures 6 in the depressed por- 35 tion below the level of the disk. In the center of the depression there is an upright hollow conical portion 7, the outer surface of which is the vaporizing surface referred to. The cone will be referred to herein as the 40 vaporizer.

Arranged around the depressed portion, preferably at equal intervals, I have shown a series of substantially rectangular openings 8 through the horizontal portion of the 45 disk. These may of course be of any convenient shape and size to give the desired air supply but I have found the arrangement shown to be most efficient. There are five openings placed at equal intervals 50 around the circumference of the depressed portion extending outward nearly to the periphery and leaving a small margin of metal adjacent the periphery which is strengthened by a suitable bead 9 which also 55 surrounds the openings in the central depression 5. Inside the bead, each of the openings 8 is surrounded by a seating surface 10. The down draft air duct casting 2 consists of a plurality of upright ducts each 60 having a radial portion 12 at the top leading to a central chamber 13 having an aperture 14 in its floor directly over the peak or truncated top 15 of the vaporizer or vaporizing cone 7. The upright ducts 11 correspond 65 in number to the openings 8 and are formed

at their lower ends at 16 to fit the seating surfaces or seats 10 surrounding the apertures 8 in which they rest.

An oil supply pipe 17 having a regulating valve 18, preferably in the form of a needle valve therein, and a drip cock 19 between the burner and the needle valve leads to the cone, a portion 20 of the pipe preferably being vertical and in alignment with the axis of the cone 7. At the top, the pipe 20 is 75 threaded or otherwise seated in the cone 7, the truncated cross-section 15 of the cone being approximately the diameter of the pipe. Just beneath the depressed portion 5, supported on the upright portion 20 of the pipe 17, I have shown a water receptacle or vaporizer 3. This is centrally apertured to admit the upright pipe 20 and supported in position by a collar 22 which preferably is arranged to be adjusted up and down the 80 pipe and held by means of a set screw 23. The water vaporizer 3 is spaced downward from the depressed portion 5 of the base plate by a short distance so that it is highly heated by radiation when the burner is in 90 operation.

In Fig. 1 I have shown the first form of the burner completely assembled and installed in a furnace. The fuel supply is contained in a low gravity tank 25. The apparatus proved by experiment to give the best results, particularly as to economy, under a gravity head of approximately one foot. The oil flows by way of a suitable feed pipe 26 to the needle valve 18 and hence by 100 the pipe 17 to the upright 20 which overflows at the top of the truncated cone, the top of the cone being cooled by the down draft from the down draft member 2, and prevents vaporization of the fuel at this 105 point so it flows down over the outer surface of the cone 7, being vaporized by the heat on the exposed surface of the cone.

Water for consumption in the burner is supplied from any suitable source as the 110 gravity tank 27, shown as placed on top of the furnace. The supply pipe 28 controlled by a shut-off valve 29 leading from this tank, branches at 30 forming two lines 31, 32 controlled by regulating valves 33, 34. The 115 pipe 32 leads to the upper part of the combustion space of the furnace terminating in a coil 35 having a central nozzle or drip opening 36 directed downward preferably on a water evaporating surface 37 near the 120 center of the air duct 2 or otherwise conveniently placed, the object being to supply water vapor to take up any carbon or high carbon gases which might otherwise escape and be wasted and possibly deposited 125 in the form of carbon. The coil serves to take up the vibration which results from the operation of the device and also gives the water a chance to become well heated so as to give easy evaporation and also to prevent 130

shock to the heated metal parts from internal stresses due to sudden changes of temperature. The pipe 31 leads to the water vaporizer receptacle 3 which serves to form steam in the vicinity of the inlet ends of the air openings so that all the air fed to the burner is charged with water vapor, it being understood that the radiation from the burner is sufficient to keep this vaporizer 5 at a temperature high enough to form steam 10 immediately from all water supplied in this way.

An advantage of the arrangement shown is that the regulating valves 33, 34 may be 15 set permanently to give the desired feed, the valve 29 being used merely as a shut-off for both nozzles.

The second form of the invention is particularly adapted for use where the draft is 20 found insufficient to convey the water vapor to the point of combustion in the proportions to the fuel and air necessary to complete combustion and the most efficient production of heat. This form is illustrated 25 in Fig. 5, the important difference being that the water instead of being vaporized in the vicinity of the air inlet openings and thus conveyed to the point of vaporization and combustion of the fuel, is delivered to the 30 surface of the fuel vaporizing cone in a manner somewhat similar to the manner of feeding the fuel as already described. In the present instance, as illustrated, this is accomplished by means of an enlarged pipe 35 40 inclosing the upright fuel pipe 20 leading to the apex of the cone. This pipe is threaded at its upper end at 41 to fit into the truncated conical fuel vaporizer 7 at a point where the inner surface of the cone reaches the requisite diameter, this pipe being fed by a suitable water pipe 42 corresponding to the pipe 31 in Fig. 1. The water is released by perforations 44 in the cone 7 between the 45 50 point where the upper end of the fuel pipe 20 is joined to the cone and the point where the water pipe is joined to the cone. These perforations, as shown, are five in number, one opposite each of the spaces between the upright air ducts 11. This brings them opposite the flame so that the water is delivered to the points of combustion at the highest temperature; this also in case an excess of water is supplied, prevents spreading of the water over the ducts, thus avoiding impact 55 of cold water on the hot casting.

In this form of the burner, the water and the fuel being both vaporized on the same surface against which the flame is projected by the inward air currents drawn through 60 the openings 6, are thoroughly commingled at the point of combustion and complete combination or burning of all the elements of the fuel to the most stable compounds or higher oxids takes place. However, it is 65 found advantageous to feed water to the top

of the down draft duct by means of the pipe 32, the coil 35 and the nozzle 36, as in Fig. 1, to provide for oxidation of any carbonaceous products which may escape from the burner proper.

Each of the burners is provided with a 70 starter ring or wick 43. In starting this wick or ring which is preferably of asbestos fiber, is saturated with kerosene, gasoline or coal oil, or the wick may be omitted and the depression 5 below the perforations 6 75 filled with starting fluid, as alcohol, kerosene or gasoline. By burning some suitable light fuel at this point, the fuel vaporizer is heated to a sufficient temperature to vaporize 80 the fuel. When the valve 18 is opened causing the fuel to mount in the pipe 20 and flow over the surface of the cone 7, as the cone has already been heated, vaporization 85 takes place and the vapor burns combining with the air drawn in through the openings 6. These air jets tend to force the flame against the cone and concentrate the heat at that point causing quick and complete vaporization of the fuel. Immediately the 90 water supply is turned on, the same being vaporized in the first form of the invention by contact with the heated plate or water vaporizer 3 at the bottom, the vapor being fed in with the air draft through the openings 95 6 and the ducts 11 and 12, or in the second form, fed to the surface of the cone from below through openings 44 so that it is vaporized with the fuel. The temperature of the cone and of the flame surrounding the cone are quickly increased, causing a corresponding increase of the draft and an increase of the temperature of the vaporizer 100 ducts 11, 12. The increase of temperature of the furnace and of the ducts 11 and 12 105 causes an increase of the draft through these members directing an air jet or draft upon the peak 15 of the cone 7, keeping this portion of the cone cool enough to prevent vaporization of the fuel until it flows down 110 the outer surfaces of the cone where it is completely vaporized in the presence of sufficient air and water to prevent carbonization. When the burner is in full operation, the cone 7 with the exception of the top portion 115 15, the down draft duct member 2, and all the parts in the immediate vicinity, are heated to a bright cherry red, and the mixing and combustion processes described take place with completeness, regularity and efficiency. It will be apparent that the exposed metal surface of the cone at such a temperature cannot in the presence of a continued supply of water vapor and air accumulate carbon and it is found that not 120 125 the slightest deposit results. The apparatus requires no attention whatever after the regulation of the fuel, water supply and furnace draft have been accomplished unless some change in the heat generated is 130

4
desired, in which case the fuel supply is correspondingly changed. In case any carbon or gases high in their percentage of carbon, or other combustible products, are 5 passed upward from the burner, a supply of hot water is dripped upon the top of the down draft air duct from the coil in both types of burner, the same being converted into steam which will combine the 10 non-burned elements, producing complete combustion in case combustion is not already complete. This extra water supply is found most efficient in eliminating all signs of carbon deposit which might result with 15 an insufficient supply of water vapor above the burner.

I have thus described my invention specifically and in detail in order that its nature and operation may be fully understood; 20 however, the specific terms herein are used descriptively rather than in their limiting sense and the scope of the invention is defined in the claims:

1. In a hydrocarbon burner, a fuel vaporizing surface arranged at an angle to the horizontal, means for supplying liquid hydrocarbon fuel to said surface to flow over the surface by gravity, draft openings directed toward the vaporizing surface and 25 substantially at right angles to said surface, and means for supplying water vapor to the inlet side of the draft openings.

2. In a hydrocarbon burner, an inclined fuel vaporizing surface, means for releasing liquid hydrocarbon fuel at the top of the incline to flow down the vaporizing surface by gravity, air draft openings directed toward the vaporizing surface and substantially at right angles to said surface, and 30 means for mixing water vapor with the fuel vapor as it is formed.

3. In a hydrocarbon burner, a conical fuel vaporizer, means for releasing liquid hydrocarbon fuel near the top of the cone to flow 35 down the conical surface by gravity, air draft openings directed toward the surface of the cone and substantially at right angles to said surface, and means for mixing water vapor with the fuel vapor as it is formed.

4. In a hydrocarbon burner, an inclined fuel vaporizing surface, means for releasing liquid hydrocarbon fuel at the top of the incline to flow down the vaporizing surface by gravity, draft openings directed toward the vaporizing surface, means for supplying water vapor to the inlet side of the draft openings, and means for supplying a downwardly directed draft of air to the top of the vaporizing surface giving an excess 45 of the oxygen for combustion and preventing vaporization of the fuel before reaching the inclined surface.

5. In a hydrocarbon burner, an inclined fuel vaporizing surface, means for releasing liquid hydrocarbon fuel at the top of 50

the incline to flow down the vaporizing surface by gravity, air draft openings directed toward the vaporizing surface, means for mixing water vapor with the fuel vapor as it is formed, and means for supplying a downwardly directed draft of air to the top of the vaporizing surface giving an excess of oxygen for combustion and preventing vaporization of the fuel before reaching the inclined surface. 75

6. In a hydrocarbon burner, a conical fuel vaporizer, means for releasing liquid hydrocarbon fuel near the top of the cone to flow down the conical surface by gravity, air draft openings directed toward the surface of the cone, means for mixing water vapor with the fuel vapor as it is formed, and means for supplying a downwardly directed draft of air to the top of the cone, giving an excess of oxygen to support combustion. 80

7. In a hydrocarbon burner in combination, a furnace inclosure with a draft inlet opening, a transverse partition above the draft inlet opening, a draft outlet opening above the partition, an upwardly projecting fuel vaporizing member having an inclined surface above said partition, means for supplying liquid hydrocarbon fuel to the surface of said vaporizing member, openings in the partition directed toward the inclined surface of said member, and means for supplying water vapor to mix with the fuel vapor as formed. 90

8. In a hydrocarbon burner in combination, a furnace inclosure with a draft inlet opening, a transverse partition above the draft inlet opening, a draft outlet opening above the partition, an upwardly projecting fuel vaporizing member having an inclined surface above said partition, means for supplying liquid hydrocarbon fuel to the surface of said vaporizing member, openings in the partition directed toward the inclined surface of said member, and means for supplying water vapor just beneath the transverse partition. 95

9. In a hydrocarbon burner in combination, a furnace inclosure with a draft inlet opening, a transverse partition above the draft inlet opening, a draft outlet opening above the partition, an upwardly projecting fuel vaporizing member having an inclined surface above said partition, means for supplying liquid hydrocarbon fuel to the surface of said vaporizing member, openings in the partition directed toward the inclined surface of said member, means for supplying water vapor to mix with the fuel vapor as formed, and means for supplying a down draft directed at the top of said fuel vaporizing member, consisting of upright passages leading from beneath the partition to a discharge opening near the upper portion of the fuel vaporizing surface. 100

10. In a hydrocarbon burner in combina-

- tion, a furnace inclosure with a draft inlet opening, a transverse partition above the draft inlet opening, a draft outlet opening above the partition, an upwardly projecting fuel vaporizing member having an inclined surface above said partition, means for supplying liquid hydrocarbon fuel to the surface of said vaporizing member, openings in the partition directed toward the inclined surface of said member, means for supplying water vapor just beneath the transverse partition, and means for supplying a down draft directed at the top of said fuel vaporizing member, consisting of upright passageways leading through the partition to a discharge opening near the upper portion of the fuel vaporizing surface.
11. In a hydrocarbon burner in combination, a furnace inclosure, a transverse partition therein with an inlet draft opening below and an outlet draft opening above, a fuel vaporizing member having an inclined surface above the partition, a depression surrounding the vaporizing member with draft openings in the outside wall of the depression directed at the inclined surface of the fuel vaporizer, means for supplying liquid hydrocarbon fuel to the top of the fuel vaporizing member to flow down the surface by gravity, means for supplying a down draft consisting of upright ducts leading through the transverse partition and discharging downwardly on the top of the fuel vaporizing member, and means for supplying water vapor at the point of vaporization of the fuel.
12. In a hydrocarbon burner in combination, a furnace inclosure, a transverse partition therein with an inlet draft opening below and an outlet draft opening above, a fuel vaporizing member having an inclined surface above the partition, a depression in the transverse partition surrounding the vaporizing member with draft openings in the partition directed at the inclined surface of the fuel vaporizer, means for supplying liquid hydrocarbon fuel to the top of the fuel vaporizing member to flow down the surface by gravity, means for supplying a down draft consisting of upright ducts leading through the transverse partition and discharging downwardly on the top of the fuel vaporizing member, and means for supplying water vapor at the entrances to the draft openings and ducts.
13. In a hydrocarbon burner, a fuel vaporizing surface at an angle to the horizontal, means for supplying liquid hydrocarbon fuel to the vaporizing surface, to be distributed over the surface by gravity, means for supplying a downwardly directed draft of air to the top of the vaporizing surface, means for mixing water vapor with the fuel vapor as it is formed, and air draft openings directed toward the vaporizing surface substantially at right angles thereto.

Signed by me at Baltimore, Maryland,
this 26 day of February, 1918.
